UNITED STATES PATENT OFFICE.

LIONEL STRASSBURGER AND CHARLES NELSON, OF BROOKLYN, NEW YORK, ASSIGNORS
TO S. STERNAU & COMPANY, OF NEW YORK, N. Y., A COPARTNERSHIP.

DESIGN FOR A CHAFING-DISH.

No. 38,889.

Specification for Design.

Patented Nov. 19, 1907.

Application filed July 17, 1907. Serial No. 384,288. Term of patent 7 years.

To all whom it may concern:

Be it known that we, LIONEL STRASSBURGER, a citizen of the United States, and CHARLES NELSON, a subject of the King of Sweden, both residing in the borough of Brooklyn, county of Kings, and State of New York, have invented a new, original, and ornamental Design for Chafing-Dishes, of which the following is a specification, reference being had to the accompanying drawing, forming part thereof.

The figure is a side elevation of a chafing dish showing our new design.

We claim:

The ornamental design for a chafing dish as shown:

LIONEL STRASSBURGER.
CHARLES NELSON.
